United States Patent

Des. 235,786
Patented July 8, 1975

235,786

DENSITOMETER OR SIMILAR ARTICLE

Gianfranco D. Zaccai, Cambridge, Mass., assignor to
Instrumentation Laboratory, Inc., Lexington, Mass.

Filed Sept. 25, 1973, Ser. No. 400,559

Term of patent 14 years

Int. Cl. D24—01

U.S. Cl. D32—2 C

FIG 1

FIG 2

FIG 3

FIG. 4

FIG. 5

FIG. 6

FIG. 7

FIG. 1 is a perspective view of a densitometer or similar article showing my new design;

FIG. 2 is a left side elevational view thereof;

FIG. 3 is a rear elevational view thereof;

FIG. 4 is a top plan view thereof;

FIG. 5 is a front elevational view thereof;

FIG. 6 is a bottom plan view thereof; and

FIG. 7 is a right side elevational view thereof.

I claim:

The ornamental design for a densitometer or similar article, as shown.
